UNITED STATES PATENT OFFICE

154,192

DESIGN FOR AN AUTOMOBILE

Preston T. Tucker, Ypsilanti, Mich., assignor to
Tucker Corporation, Chicago, Ill., a corporation
of Delaware

Application March 15, 1947, Serial No. 137,626

Term of patent 3½ years

(Cl. D14—3)

To all whom it may concern:

Be it known that I, Preston T. Tucker, a citizen of the United States, residing at Ypsilanti, in the county of Washtenaw and State of Michigan, have invented a new, original, and ornamental Design for an Automobile, of which the following is a specification, reference being had to the accompanying drawings, forming a part thereof, wherein:

Figure 1 is a view in side elevation of an automobile embodying the design of this invention;

Figure 2 is a top plan view;

Figure 3 is a view in front elevation; and

Figure 4 is a rear end elevational view.

The characteristic features of my design reside in the portions shown by means of full lines in the drawings.

I claim:

The ornamental design for an automobile, substantially as shown and described.

PRESTON T. TUCKER.
